LEON F. HOFFMAN, OF FRANKLIN, PENNSYLVANIA, ASSIGNOR TO CHICAGO PNEUMATIC TOOL COMPANY, OF NEW YORK, N. Y., A CORPORATION OF NEW JERSEY.

STARTING UNLOADER FOR AIR COMPRESSORS.

Application filed May 28, 1921. Serial No. 473,357.

To all whom it may concern:

Be it known that I, LEON F. HOFFMAN, citizen of the United States, residing at Franklin, in the county of Venango and 5 State of Pennsylvania, have invented certain new and useful Improvements in Starting Unloaders for Air Compressors, of which the following is a specification.

The object, construction and operation of 10 my improved starting unloader for air compressors, are herein set forth with sufficient clearness to enable those skilled in the arts to which its construction and use respectively relate, to make and use the same.

15 In the operation of air compressors, it is almost invariably the practice to provide a storage tank for the compressed air, which is termed the receiver, and into which the discharge pipe of the compressor leads.

20 After the initial starting and operation of an air compressor, there is thereafter maintained a practically continuous pressure of air in this receiver, and each time the compressor is started, it meets with a 25 resistance equal to this pressure in the receiver. It is desirable therefore that some convenient, expeditious, efficient and automatic means be employed to eliminate or avoid this pressure at the time of starting 30 the compressor, so that it may start with a minimum strain upon the driving power and the various operating parts, of both the air compressor and said power.

This is true with reference to nearly any 35 type of motive power, and is especially so in case an electric motor is employed for this purpose, in order that the starting torque may be reduced to a minimum; it may be less important, however, in case 40 steam power is employed.

It is the object of this invention to supply means whereby the above results may be attained.

Various forms whereby the mechanical 45 embodiment of my inventive idea may be expressed and practiced, will be suggested by the drawings and the specification which follows, but, as usual, the precise definition of my invention is to be found in the appended claims.

In said drawings which form a part hereof:

Fig. 1 is a side elevation of an electrically-driven air compressor, equipped with 55 my improved starting unloader.

Fig. 2 is a vertical section of the control valve which constitutes the primary element of this invention, the operative elements of the valve being here shown in relation to the main structure in the unloading position.

Fig. 3 is a section or portion of said valve with said elements shown in the relation to the main structure which they occupy in the loaded position.

Fig. 4 is an elevation of said control valve, having a speed actuating device in the form of a centrifugal governor.

Fig. 5 is an elevation of the reverse side of the regulating valve body.

Fig. 6 is an inverted plan view of the valve which is attached to the stem of the centrifugal governor.

Fig. 7 is a schematic section of the regulating valve and a certain form of air compressor unloader valve showing both these organizations in the unloading and starting positions.

Fig. 8 is a schematic section showing said organizations in the loaded position, as when the compressor is normally operating.

It will be of assistance to a ready understanding of the construction illustrated and immediately hereafter described, to state that the centrifugal organization—shown in Fig. 4, and which constitutes the actuating mechanism of the operative elements within the regulating valve, may be any well-known form and type of centrifugal governor, such as is commonly used upon steam engines; that which is termed the "body" of the governor, and the valve used in steam or gas engine practice are dispensed with, and the body and valves shown in Fig. 2 are substituted therefor, said body and its valves being, as previously stated, the primary portion of this invention.

The construction illustrated in said drawings is as follows:

A regulating valve is employed which consists of a body 1 provided with a flange 2 for the reception and attachment of the flange 3 of a centrifugal governor of any suitable type. The relative position and attachment of the centrifugal organization is such that the valve stem 4 thereof extends within what is termed the receiver chamber 5 of said body 1. Said receiver chamber 5 is divided from the unloader chamber 6 in said body 1 by a partition 7 arranged to

form a seat for a by-pass valve 8, which is attached to and actuated by said stem 4.

A pipe or conduit 9 which leads to a receiver, or source of air supply under pressure, enters said receiver-chamber 5 and affords constant communication between said chamber 6 and said receiver or source of air supply. (If, however, it is desirable, a globe valve or a stop cock may be interposed in said pipe 9, as an emergency provision). A pipe or conduit 10 leads from said unloader chamber 6 to the cylinder 11 of the unloader valve of the air compressor.

Said partition 7 is centrally pierced, and the resulting port is formed at the upper face of the partition, into a seat 12 for the seating of the corresponding face 13 of said by-pass valve 8. Said valve 8 terminates in a triangular guide 8'—Fig. 6—which has free longitudinal movement through said port of the wall 7; the lower end of said guide 8' is adapted to contact with the upper adjacent end of the valve-stem 16, as hereafter stated. The triangular form of said guide 8' is for the purpose of allowing a free passage of air along the same from chamber 5 to chamber 6.

Within the bottom wall of body 1 is introduced a valve seat bushing for the support and reception of a relief valve 15. Said seat 14 is externally threaded to enter a correspondingly threaded port therefor in said body 1. The threaded portion of this seat is somewhat elongated, whereby it is adapted to have a certain amount of longitudinal adjustment, for a purpose that will later appear.

The valve 15 is provided with a stem 16 which projects through said seat and its inner end is surrounded with a compression spring 17, which, after being somewhat compressed, is secured in position by means of a washer 18 and a cotter pin 19, whereby said valve is firmly but yieldably retained upon its seat in said bushing 14.

The centrifugal organization may be operated either from the crank-shaft of the compressor, or from the shaft of the motor, but for various reasons, the crank-shaft of the air compressor is preferred.

In Fig. 1 is shown a belt 21 which passes around a pulley 22 upon the crank-shaft of 23 of the compressor and the pulley 24 of the centrifugal organization, whereby transmission of motion from the crank-shaft of the compressor to the pulley shaft of the governor is effected.

When the air compressor is not running, the stem 4 of the governor occupies a position such as to hold the by-pass valve 8 in the position shown in Figs. 1 and 7, which is the unseated position of said valve 8, and in this position air passes from the receiver through the regulator valve to the cylinder 11 of the unloader valve, as shown in Fig.

7. The result of this is to hold the valve of the compressor open so that instead of said compressor valve performing its natural function, there is a regurgitative action of the air at this valve, and hence no power is consumed or required in compressing air and forcing it into the receiver against the pressure therein, and this is what is termed the "unloaded" state of the compressor; the only power required to operate it is such as to overcome mechanical friction.

When the motive power generator,—in this case the motor—has arrived at normal speed, the action of the centrifugal organization will cause the stem 4 and the there-to-attached valve 8 to move downward so that said valve is firmly seated, as shown in Figs. 3 and 8, thus closing communication between the receiver and the unloader valve.

At the same time, the lower end of guide 8' comes into contact with stem 16, and unseats valve 15, thus permitting the escape of air from the unloader valve, whereupon the air compressor assumes its normal function.

The object of providing the vertically-adjustable bushing 14 and seat for said valve 15, is, to eliminate the necessity of accurately gauging the distance between seat 12 and the seat 15, and also to provide ample room for the spring 17 so that it will never be fully compressed and prevent the proper seating of the by-pass valve 8'. This adjustment also provides means for regulating and determining to a certain extent, the time at which air will be released from the unloader-cylinder.

Many types of unloaders for air compressors are adapted to be operated by means of my improved regulating valve. However, for the sake of clearness and completeness of this description, I will explain the unloader valve illustrated in the drawing.

An inlet valve organization for an air compressor is shown in Figs. 7 and 8. To said valve organization, an unloader is applied which comprises a valve actuator 26, which is held in alinement by and adapted to have movement longitudinally upon the stud 27 that is carried centrally by the valve organization; the lower extremities of its respective forks 28 of said actuator are yieldably supported out of contact with the valve plate 29 by the compression spring 30, as shown in Fig. 8.

An actuating cylinder 11 is carried by the cover 31 for the valve port; said cylinder is concentric with the stud 27, and in the same is mounted a piston 32, having a bifurcate lower end which bears upon the upper end of said actuator; the upper end of said piston is provided with a suitable packing 33, whereby said piston is made suitable for actuation by compressed air.

A suitable cover is provided for said cylinder 11, into which the conduit 10 enters.

As air under pressure enters the cylinder, the piston 32 is actuated downwardly, 5 pressing spring 30, and as the forks 28 of the actuator come into contact with the plate valve 29, it is moved from its seat to the retaining member 35, in opposition to the compression springs 36. As soon as air is 10 released from said cylinder, the spring 30 returns the actuator 36 to its upward, normal position.

I claim the following:

1. A starting unloader for air compressors comprising, in combination, an unloader for said compressor, a supply of air under pressure, a conduit for the passage of air from said supply to said unloader by which said unloader is actuated into its unloading 20 position, when the compressor is stopped, a normally-open valve interposed in said conduit, centrifugal means driven by the compressor closing said valve after the compressor is started by which said passage of 25 air is arrested, and adjustable means releasing the residual air in said conduit between said valve and said unloader upon the closing of said valve, whereby said unloader is permitted to discontinue its unloading 30 functions.

2. A starting unloader for air compressors comprising, in combination, an unloader for said compressor actuatable to its unloading position by air under pressure, a supply 35 of air under pressure, a conduit for the passage of air from said supply to said unloader, a valve in said conduit, means automatically maintaining said valve in the open position for the passage of air there- 40 through to the unloader when the compressor stops and closing the same to cause the discontinuance of said passage of air after the compressor has started, and adjustable means automatically releasing the actuating 45 air from the unloader upon the closing of said valve.

3. In a starting unloader for air compressors, a pneumatically-actuated unloader for the compressor, a source of actuating 50 air for said unloader, a conduit for the passage of air from said source to said unloader, a regulating valve organization interposed in said conduit comprising a body having a chamber therein which is divided 55 by a partition wall into two compartments from one of which, termed the receiver compartment, said conduit leads to said source of actuating air, and from the other, termed the unloader compartment, said conduit 60 leads to said unloader, said partition wall having as a feature thereof a port connecting said compartments, a valve adapted to open and close said port, centrifugal means operated by the compressor connected to 65 said valve and arranged to hold the same in

the open position when the compressor is stopped and to actuate said valve into the closed position when the compressor has reached a pre-determined speed, and a spring-closed relief valve for said unloader 70 compartment actuatable to the open position by the closing movement of said first-mentioned valve for the release of actuating air from said unloader.

4. In a starting unloader for air compressors, a pneumatically-actuated unloader for the compressor, a source of actuating air for said unloader, a conduit for the passage of said actuating air from said source to said unloader, a regulating valve organization interposed in said conduit comprising a body having a chamber which is divided by a partition wall into two compartments from one of which, termed the receiver compartment, said conduit leads to 75 said source of actuating air, and from the other, termed the unloader compartment, said conduit leads to said unloader, said partition wall having as a feature thereof a port connecting said compartments, a valve adapted to open and to close said port, centrifugal means operated by the compressor connected to said valve arranged to hold the same in the open position when the compressor is stopped and to actuate said valve 80 to its closed position when the compressor has reached a pre-determined speed, a normally closed, yieldable relief valve for said unloader compartment actuatable to its open, relief position by the closing action of said 85 first mentioned valve, and an adjustable mounting for said relief valve whereby its opening movement may be varied relative to the closing movement of said first-mentioned valve.

5. In a starting unloader for air compressors comprising, in combination, an air compressor provided with an unloader, a supply of air under pressure, a conduit for the passage of air from said supply of air 100 to the unloader, a normally open valve interposed in said conduit permitting the passage of air from said supply to said unloader to actuate the same into its unloading position when the compressor is not 105 running, speed-actuated means closing said valve to discontinue said passage of air at a predetermined speed of said compressor, and adjustable means releasing the actuating air from said unloader cylinder upon 120 the closing of said valve.

6. In a starting unloader for air compressors, a pneumatically-actuated unloader for said compressor, a source of actuating air for said unloader, a conduit for the passage of said actuating air from said source to said unloader, a regulating valve organization interposed in said conduit comprising a body having a chamber which is divided by a partition wall into two compartments 125

ments, from one of which, termed the receiver compartment, said conduit leads to said source of actuating air, and from the other, termed the unloader compartment, 5 said conduit leads to said unloader, said partition wall having as a feature thereof a port connecting said compartments, a valve adapted to open and to close said port, the wall of said unloader compartment having as a feature thereof a release port leading 10 to the atmosphere, a spring-actuated valve normally closing said release port, and centrifugal means operated by the compressor connected to said first-mentioned

valve arranged to hold the same in the open 15 position when the compressor is stopped and to actuate the same to the closed position when the compressor has reached a pre-determined speed; said spring-actuated valve being adapted to be actuated to its open position by the closing action of said first-mentioned valve.

In testimony whereof I affix my signature in presence of two witnesses.

LEON F. HOFFMAN.
